UNITED STATES PATENT OFFICE

148,077

DESIGN FOR A POLISHING HEAD

Max Leach, Providence, R. I., assignor to H. Leach
Machinery Co., a corporation of Rhode Island

Application December 29, 1945, Serial No. 125,146

Term of patent 14 years

(Cl. D37—1)

To all whom it may concern:

Be it known that I, Max Leach, a citizen of the United States of America, residing at Providence, county of Providence, State of Rhode Island, have invented a new, original, and ornamental Design for a Polishing Head, of which the following is a specification, reference being had to the accompanying drawing, forming a part thereof.

Fig. 1 is a front elevation showing my new design for a polishing head; and

Fig. 2 is an end view thereof with spindles omitted for convenience of illustration.

The dominant features of the design reside in the portions shown in full lines.

I claim:

The ornamental design for a polishing head, substantially as shown and described.

MAX LEACH.
